UNITED STATES PATENT OFFICE.

WILLIAM OSCAR VAN ORMER, OF OSCEOLA, MISSOURI.

DOOR-HOLDER.

1,081,795.

Specification of Letters Patent.

Patented Dec. 16, 1913.

Application filed December 31, 1912. Serial No. 739,492.

To all whom it may concern:

Be it known that I, WILLIAM O. VAN ORMER, citizen of the United States, residing at Osceola, in the county of St. Clair 5 and State of Missouri, have invented certain new and useful Improvements in Door-Holders, of which the following is a specification, reference being had therein to the accompanying drawing.

10 This invention relates to a door stop and catch, and comprises two parts, one of which is attached to the door and the other to the base board of the wall near the door.

15 The object of this invention is the production of a receiving socket which may be formed from a blank and which is provided with an enlarged portion which is adapted to facilitate the placing of the socket upon a support.

20 With these and other objects in view this invention consists of certain novel combinations, constructions, and arrangements of parts as will be hereinafter fully described and claimed.

25 In the accompanying drawing:—Figure 1 is a perspective view of the stop and catch illustrating how the same may be used. Fig. 2 is a side elevation of the device showing a part of the same in section. Fig. 3 is a 30 plan view of the blank from which the receiving socket is formed. Fig. 4 is an enlarged sectional view of the thickened portion of the receiving socket showing a portion of the receiving socket in section.

35 Referring to the accompanying drawing by numerals it will be seen that the device is used in combination with a door 1 and the base board 2. The door 1 carries the ball which comprises a screw 3 which is 40 screwed into the door. The screw 3 is provided with the integral plate 4, which is adapted to limit the inward movement of the screw 3. A threaded portion 5 is formed upon the outer portion of the screw 45 3 which is adapted to be threaded into the hollow threaded portion 6 of the ball 7. By use of this device it will be seen that the screw may be first placed in the door and after which the ball may be placed upon 50 the threaded portion without damaging or marring the ball 7.

The stop and catch portion comprises a screw 8 which is adapted to be placed or screwed into the base board. The screw 8 extends to form a body portion 9, said body 55 portion 9 provided with a centrally located squared portion 10, whereby the device may be screwed into the base board 2. In order to limit the inward movement of the catch there is provided a bell shape stop 11 upon 60 the inner portion of the body 9.

A receiving socket which is adapted to receive and hold the ball 7 is formed from a blank and is provided with a plurality of reduced arm portions 12 which are provided 65 with the enlarged head 13. These arms are adapted to be bent so as to constitute a receiving socket for catching the ball. Centrally located in the body portion of the receiving socket is an aperture 14. The inner edge 15 is adapted to be forced back as illustrated in dotted lines at 16. In this manner there is provided an enlarged thickened body 17 which is adapted to be threaded upon the threaded portion 18 of the body 75 9. By use of this thickened body the receiving socket is held securely upon the body 9 and will always remain firm even after constant use.

In order to facilitate the insertion of the 80 screw 8 into the base board 2, the body 9 is provided with a transversely extending groove 19 upon its outer end which is adapted to receive a screw driver or other suitable means for screwing the portion 8 into the 85 support. The threaded portion 5 of the screw 3 which is carried by the door is provided with a transversely extending groove 19 which is formed similar to the groove formed in the body 9. The ball 7 is also 90 provided upon its outer portion with a groove 20 which is adapted to facilitate the removal or the threading of the same upon the threaded portion 5. By the use of these slots it will be possible for a person to place 95 the entire device in an operative position upon a support and the door by the use of a screw driver.

Having thus described the invention what is claimed as new, is:—

100 A socket for door holders formed from a sheet of resilient material having a central

thickened portion formed by crowding the material to provide an internally threaded sleeve, and having arms radiating from the sleeve and bent forwardly to provide a resilient wall that surrounds said sleeve, and a wall engaging support having a threaded end for engaging the threaded sleeve.

In testimony whereof I hereunto affix my signature in presence of two witnesses.

WILLIAM OSCAR VAN ORMER.

Witnesses:

P. B. LISNUER,
EDWIN M. COX.
